UNITED STATES PATENT OFFICE.

JOHN CALLAN, OF RAY, ARIZONA.

HOSE SUPPORTER.

Application filed June 29, 1921. Serial No. 481,372.

To all whom it may concern:

Be it known that I, JOHN CALLAN, a citizen of the United States, residing at Ray, in the county of Pinal and State of Arizona, have invented certain new and useful Improvements in a Hose Supporter; and I do hereby declare the following to be a full, clear, and exact description of the invention, such as will enable others skilled in the art 10 to which it appertains to make and use the same.

The invention relates to means for retaining hosiery in proper position and is designed particularly for long stockings which 15 extend well above the knee and require to be supported at their upper ends.

The invention consists of a garter embodying a portion of rigid material having an arm projecting therefrom to extend upwardly along the leg above the knee to engage the upper end of the stocking and prevent it from slipping down.

Other objects and advantages will be apparent and suggest themselves as the nature 25 of the invention is understood.

While the drawings illustrate an embodiment of the invention it is to be understood that in adapting the same to meet different conditions and requirements, various 30 changes in the form, proportion and minor details of construction may be resorted to without departing from the nature of the invention.

Referring to the accompanying drawings 35 forming a part of the specification,

Figure 1 is a perspective view of the device.

Figure 2 is a side view of the supporter showing the same applied.

Figure 3 is a detail view of a portion of 40 the supporter showing the manner of connecting one end of the elastic thereto.

Figure 4 is a detail view similar to Figure 3 of a modification.

Corresponding and like parts are referred 45 to in the following description and designated in the several views of the drawings by like reference characters.

The supporter is made in rights and lefts 50 and comprises a garter for encircling the leg and an arm projecting from the garter and adapted to extend upwardly along the side of the leg to engage the upper portion of the stocking and retain the same in 55 proper position. The garter portion of the supporter comprises a portion formed of

rigid material such as celluloid, hard rubber, or other composition, or metal and a portion constructed of elastic, tape or similar material. The garter portion of the supporter is designed to be applied to the leg just above the knee with the arm extending upwardly along the outer side of the leg to engage the upper portion of the stocking and retain the same in the desired adjusted position. The portion constructed of rigid material comprises a semi-circular band 1 and an arm 2 projecting therefrom so as to occupy an upward position when the supporter is in place. The arm 2 is disposed at one end of the band 1 and forms an obtuse angle therewith to admit of the arm extending upwardly and forwardly so as to engage the upper end of the stocking near the front thereof. Each supporter has 70 one arm only and the same is arranged to extend along the outer side of the leg. The band 1 and arm 2 are preferably of integral formation. The ends of the band 1 curve outwardly to avoid injurious and annoying 75 pressure upon the side of the leg. The lining 3 is applied to the inner side of the band 1 and is secured thereto in any manner. In the preferable construction the lining 3 is stitched along its edges to the edge 80 portions of the band 1, the latter being provided along its edges with openings to receive the stitching. A keeper 4 is provided at each end of the band 1 and consists of a portion of the band pressed outwardly between parallel slits or cuts. The band 1 85 is designed to occupy the rear portion of the leg above the knee and is held in place by an elastic 5 which is attached at its ends to the ends of the band 1 by means of the 90 keepers 4. The loose ends of the elastic 5 are adapted to be adjustably connected to the keepers 4 to admit of adjusting the supporter to the size of the limb. As indicated in the drawings, the loose ends of the elastic 95 and passed through the keepers 4 are returned upon themselves and pass between the elastic and the band 1 and are usually folded over the main portion of the elastic 100 and passed between it and the return portions extending over the keepers 4. Obviously the loose ends of the elastic may be fastened in any preferred or convenient way to render the same secure after the garter portion of the supporter has been adjusted to the limb. A lining 7 is applied 105 to the inner side of the elastic 5 to obviate

110

annoying pressure upon the front portion of the leg. The lining 7 may be secured to the elastic 5 in any manner so as not to interfere with the stretching of the elastic 5 when placing the device in position or removing it from the limb.

An end portion of the elastic 5 is provided with one or more button holes 6 to cooperate with a button 8 attached to the elastic, 10 whereby a purse sling may be provided for the reception of a pocket book or other article for safe keeping.

The upper end of the arm 2 is provided with a slot 9 through which a portion of the 15 stocking is drawn whereby to secure the same. The fold of the stocking after being drawn through the slot 9 is engaged over the upper end of the arm 2 whereby the same is made secure against possible 20 placement under ordinary conditions of use.

When the supporter is in position it is located upon the leg above the knee with the band 1 in the rear and the elastic 5 to the front. The supporter may be drawn upon 25 or off the leg in substantially the same manner as the usual garter, or if preferred, may

be placed in position about the limb or removed therefrom in a similar manner. The device enables the upper ends of stockings to be supported in a comfortable and neat 30 way and prevents their slipping down on the limb which is objectionable.

Having thus described the invention, what I claim is:—

A hose supporter comprising a semi-circular band of rigid material, a rigid upwardly and forwardly inclined arm formed integral with and at one end of said band, 35 said arm having means at its upper end to engage the top of the hose to support the same, and a strip of elastic extending between the ends of the band and cooperating with the band to form a circular garter to support the lower part of the hose and the 40 upwardly inclined arm.

In testimony whereof I affix my signature in presence of two witnesses.

JOHN CALLAN.
